UNITED STATES PATENT OFFICE.

GEORGE B. OWEN, JR., OF BROOKLYN, NEW YORK.

AIR-MOISTENING DEVICE.

1,129,897.

Specification of Letters Patent.

Patented Mar. 2, 1915.

Application filed May 16, 1914. Serial No. 839,069.

To all whom it may concern:

Be it known that I, GEORGE B. OWEN, Jr., a citizen of the United States, residing at Brooklyn, Kings county, New York, have 5 invented certain new and useful Improvements in Air-Moistening Devices, of which the following is a full, clear, and exact description.

The present invention relates to an air 10 moistening device of simple construction which is of particular utility and advantage when used for moistening cigars and tobaccos, inasmuch as it provides means for the slow and regular diffusion of moisture 15 into the air surrounding the tobacco and may be readily adapted to a large variety of forms and conditions.

One embodiment of the invention is illustrated in the accompanying drawings forming 20 part of this specification, and in which—

Figure 1 is a vertical sectional view through a liquid container embodying the present invention. Fig. 2 is a top plan view 25 of the container shown in Fig. 1. Fig. 3 is an enlarged detail view of the moisture-diffusing plug. Fig. 4 is a vertical sectional view through the container showing a modified form of the invention.

Tobacco moisteners, as previously constructed, have been objectionable because of the fact that they rapidly evaporate moisture until the source is exhausted, producing a too moist condition of the atmosphere; and thereafter are of no further use, making 35 it necessary to give them attention at very short intervals. My improved form of moistening device is designed to provide moisture diffusing means which will diffuse constantly, evenly and gradually, and which 40 has the added advantage of providing means whereby the amount of diffusion may be regulated to suit varying conditions.

In the drawings, 1 designates a suitable liquid container which may be of any shape, 45 size and non-porous material, and which may have therein a suitable outlet aperture which is closed or plugged by the diffusing device of the present invention. I provide preferably an outer stopper member of suitable material, such as the cork 2, which fits firmly into the outlet aperture of the container. This stopper is centrally apertured 50 to receive a diffusing plug 3 of suitable cross sectional shape and preferably of greater length than the thickness of the stopper 2. 55 This plug is constructed of porous stone,

one suitable material being terra cotta, and in the forms shown in Figs. 1, 2 and 3 of the drawings, is provided with an integral wick portion 4 of materially reduced diameter relative to the main body 3 and depending therefrom, this wick portion being of sufficient length to enable its lower end to be positioned adjacent the bottom of the container. The main body 3 of the plug fits tightly in the central aperture of the stopper 2 and may be moved upwardly and downwardly relatively to said stopper to expose more or less of the area of its upper end to the atmosphere. The lower portion 4, in the form shown in Figs. 1-3 of the drawings, is of the same material as the body portion 3 and acts as a wick to draw up the liquid 6 in the container by capillary attraction so that this liquid is drawn up through the wick portion 4 into the main body 3 of the plug from whose exposed upper end it is diffused into the atmosphere. In order to permit this capillary action, the container must be provided with an air 70 vent, as will be obvious. One desirable way of providing such a vent is to provide the longitudinal face of the main plug 3 with a groove 5 extending from end to end thereof. This groove may be formed therein 75 when the plug is molded or otherwise formed and would be of such depth as to prevent closure thereof by the compressed material of the stopper 2 against which the edge of the plug is forced.

In Fig. 4 of the drawings I have illustrated a modification wherein 1^a designates the container, 2^a the stopper member and 3^a the moisture diffusing plug having a suitable air inlet groove 5^a therein, as above described. Instead, however, of providing a wick portion formed of the same material and integral with the plug 3^a, the latter may be formed in its bottom face with one or more sockets 7 in which a suitable wick 8 100 may be secured, this wick being of any suitable fibrous material and extending down to rest adjacent or upon the bottom of the container. The length of the wicking would be such as to permit adjustment of the plug 3^a 105 without withdrawing the bottom of the wicking material from the bottom of the container as in the first form of the invention described.

The porous stone material of the plug 110 provides a relatively minute cellular structure which gradually absorbs moisture with-

out disintegration, and which gradually diffuses said moisture into the atmosphere. Such a substance is illustrated by the familiar terra cotta, but there are various 5 other stones, or mineral substances whose cellular formation is suitable, and it will also be obvious that artificial mineral compounds other than terra cotta may be employed, although the latter is very desirable 10 and gives very satisfactory results. The adjustment of the exposed end of the porous plug relatively to the stopper is particularly advantageous as it permits the area of the diffusing surface to be diminished or increased, according to the requirements of 15 each particular case.

What I claim, therefore, and desire to secure by Letters Patent is:

1. An air moistener of the character described, comprising a liquid container having an outlet opening therein with a closure for said opening, including an outer body and a porous plug of mineral composition and relatively minute cellular structure extending through said body, and adjustable 25 relatively thereto to vary the area of the moisture diffusing surface exposed to the atmosphere, said plug having a wick portion extending within the container to conduct 30 liquid to its exposed surface.

2. An air moistener of the character described, comprising a liquid container having an outlet opening therein, with a closure for said opening including an outer stopper body of compressible material, and a porous 35 plug of mineral composition extending therethrough, said plug having a wick portion within the container arranged to conduct liquid to its exposed moisture diffusing surface. 40

3. As an article of manufacture, a stopper comprising an outer portion of compressible material, having a porous plug of mineral composition extending therethrough, the inner end of said plug having a wick portion. 45

4. As an article of manufacture, a stopper comprising an outer portion of compressible material, having a porous plug of mineral composition extending therethrough, the inner end of said plug having a wick portion 50 and the sides of said plug having frictional engagement with said outer portion whereby it may be adjusted relatively thereto to vary the area of moisture diffusing surface exposed to the atmosphere.
